(57) **CLAIM**

The ornamental design for postage label, as shown and described.

DESCRIPTION

FIG. 1 is a top plan view of a postage label showing my new design;

FIG. 2 is a front elevational view thereof, the rear elevational view being identical;

FIG. 3 is a right side elevational view thereof, the left side elevational view being identical;

FIG. 4 is a bottom plan view thereof; and,

FIG. 5 is an enlargement of a portion of a line of microprinting vertically disposed on the left side of the top plan view of FIG. 1 and being spaced from the left edge by the shaded region, the content of the line of microprinting forming no part of the claimed design.

Phantom lining, where utilized, is for illustrative purposes only, and is not intended to limit the claimed design to the features shown in phantom.
